UNITED STATES PATENT OFFICE.

LAWRENCE DENNISON, OF BROOKFIELD, ILLINOIS, ASSIGNOR TO GENERAL CAN COMPANY, OF CHICAGO, ILLINOIS.

SANITARY CAN-CLOSING MACHINE.

Application filed June 7, 1919. Serial No. 302,491.

To all whom it may concern:

Be it known that I, LAWRENCE DENNISON, a citizen of the United States, residing at Brookfield, in the county of Cook, in the State of Illinois, have invented a new Sanitary Can-Closing Machine.

My invention relates to improvements in can closing machines of the type in which the can and cover are held stationary while the seaming rollers rotate about them during the seaming operation.

One object of the present invention is to provide means whereby a quick adjustment of the machine may be made by an unskilled person to adapt the machine for cans of any size within its capacity. Another object is to provide an improved machine of this character by means of which spilling of the liquid contents of the can is prevented. An other object is to provide means for so holding the can as to ensure a circular cross section thereof while the cover is being attached. An additional object is to provide an improved and generally simplified machine of the type described.

In the accompanying drawings in which I have illustrated one embodiment of the invention—

Figure 1 is a front elevation of the machine; Fig. 2 is a side elevation thereof; Fig. 3 is a plan view thereof; Fig. 4 is a perspective view of a cam lever and pin for effecting height adjustment; Fig. 5 is a plan view of the cover magazine adjusted to its minimum size; Fig. 6 is a similar view, the magazine being adjusted to maximum size; Fig. 7 is a sectional elevation on the line 7—7 of Fig. 5; Fig. 8 is a plan view of a shutter for rounding the cans; Fig. 9 is a plan view of a rotary conveyor; Fig. 10 is a half elevation and half section (on the line 10—10 of Fig. 9) of said rotary conveyor; Fig. 11 is a plan view of the seaming head; Fig. 12 is an elevation of said seaming head; Fig. 13 is a view of one of the dowel pins; Fig. 14 is a vertical section on the line 14—14 of Fig. 3 with certain parts omitted; Fig. 15 is an elevation of said seaming head; Fig. 16 is an elevation of the cover-releasing mechanism; Fig. 17 is a central section through the machine with certain pivoted levers and a shutter omitted; and Fig. 18 is a similar section at right angles thereto with parts in elevation.

The machine comprises a suitable base, or

standard, 1, on which the seaming mechanism and adjuncts are mounted. The power is derived through tight and loose pulleys 2, 3, which drive bevel gears 4, thereby rotating a vertical shaft 5. At the upper end 60 of the shaft 5, gears 6, 7 are provided which operate the double seaming rollers herein-after described. At a lower point on said shaft 5 a pinion 8 is provided which drives the gear 9, shaft 10, pinion 11, gear 12, shaft 13, gear 14, and shaft 15. The vertical shaft 10 drives the spiral gears 16, 17, the latter being mounted on a shaft 18 and driving the belt pulley 19 and belt 20 which is supported also by the pulley 21, this belt 70 constituting the feeding mechanism for advancing the cans to the point where the cover is applied thereto. The gearing is shown for illustrative purposes only, the specific disclosure thereof forming no part 75 of applicant's invention. The vertical shaft 13 is provided at its upper end with cam mechanism for raising and lowering the can to press the top of the same against the seaming mechanism. It is also provided 80 with Geneva stop mechanism for intermittently rotating the star wheel which feeds the cans one at a time to the seaming mechanism. The vertical shaft 15 is provided with cam mechanism at its upper end for 85 moving the seaming rollers radially inward and for operating the ejector hereinafter described.

The can covers are stacked in the magazine which will now be described. It consists of a base plate 22 on which are mounted a plurality of pins 23, each pin has pivotally mounted thereon an arm 24, each arm carrying a vertical rod 25. Said rods may thus be swung about the axes of the pins 23 90 and may be moved toward or away from each other to accommodate covers 26 of different diameters. In order to move said rods simultaneously, a ring 27 is provided having a plurality of radial slots 28 therein (Figs. 100 5 and 6) each of which receives a pin 29 projecting downwardly from one of the arms 24. The rotation of the ring therefore moves said rods 25 toward and away from each other. The said ring is provided with a plurality of openings 30 through any one of which a pin 31 may be inserted to register with a single opening in the base 22, thereby locking said ring in any one of a number 105 of predetermined positions. As previously 110

stated, the cans are fed to the machine by the belt 20, the forward movement being arrested by a star wheel 32 which turns about the shaft 15. This star wheel is made in three sections 33, 35, 35, which are relatively adjustable and may be locked in any desired position by means of the tapering pin 36, which passes through any one of a plurality of holes in each of said plates. As will be seen from Fig. 9; the upper section, or plate, has a plurality of radial extensions, one side of each of which has an arc-shaped recess 37, the lower plate having similar arc-shaped recesses 39 on the opposite side of said projection; the intermediate plate 34 has a plurality of eccentrically curved surfaces 40 which limit the inward radial movement of the can. Adjustment of these three plates is effected by relative rotation thereof, thereby forming recesses adapted to receive cans of different diameters and provide a three-point contact therewith. With this arrangement, cans of all standard sizes are not only held securely, but it is not necessary to replace the star wheel whenever a can of different size is to be operated on. The said star wheel turns with a sleeve 41 on the shaft 15, said sleeve being rotated by a Geneva stop mechanism, comprising a driven wheel 42 and a driving wheel 43, the latter turning with the shaft 13. This arrangement provides for intermittent rotation of the star wheel, thereby sweeping the cans in a circular path one at a time from the belt to the seaming rollers. Prior to this movement the cover is applied to the can in the following manner:

The plate 22 has an opening 44 therein large enough to accommodate the largest cover, the stack of covers resting on a pair of arc-shaped rails 45. As the star wheel rotates a pivoted lever 46, of which there are six carried by said star wheel, is so arranged that its outer end rides upwardly on the rail 47, causing it to strike the lowermost cover and slide it along the rails 45 to a point over the belt which feeds the cans to the star wheel. At the end of this movement said cover has slid on to and is supported by a pair of hooks 48 pivoted at a point 49 and arranged to have their lower ends moved apart in order to drop the cover on to the can beneath, said movement being caused by a yoke 50 which is lowered by the rod 51 thereby causing the pins 52 to slide in the inclined slots 53 and move the upper ends of said levers toward each other. The rod 51 is lowered intermittently by a lever 54 which turns with a shaft 55 having a second lever 56 thereon, the latter being rocked by a rotatable cam 57, said cam turning with the shaft 15. The rod 51 is provided at its lower end with a plate 58 forming a plunger which presses the cover into the top of the can and is thereafter elevated slightly to

relieve the pressure but not enough to permit the cover to spring out of the can, or loosen sufficiently to enable the can to spill its contents as it is being moved to one side by the star wheel. During such movement, the cover is further held in place by a stationary plate 59, until the can has been moved through approximately 60° to the spinning rollers 60, 61.

As soon as the can reaches the seaming rollers, it is pressed upwardly and is automatically centred by the device shown in Fig. 8. This mechanism consists of a stationary ring 70, which ring carries a series of pivoted plates 71 which may be made to swing inwardly to form substantially a circular opening of variable diameter. Said individual plates are moved by a lower ring 72 provided with slots 72' and with an arm 73, the latter being rocked by a cam roller 74 carried by a rotating hub 75 which turns with the shaft 15. Each plate 71 is pivoted about a pin 71' secured to the upper ring 70 and each has a pin 71'' projecting downwardly into one of the slots 72'. The plate 72 is normally held in such position by the spring 76 as to make the opening as large as possible under a given adjustment. This position is determined when the pins 71'' reach the outer end of the slots 72'. When the arm 73 is moved in opposition of the action of the spring by the roller 74, the minimum diameter of the opening is positively determined by movement of said arm and by the prior adjustment of the upper plate 70 with reference to the lower plate. The said plate may be locked in any one of a number of positions of adjustment by means of a pin 77 passing through any one of a number of holes 78 and passing also through an opening in a projection on the stationary supporting housing 79. The function of this centering device is to accurately center the can with reference to the seaming rollers and also to force the can to assume a cylindrical form in case the upper end is not accurate in this respect.

The upward movement of the can occurs simultaneously with the centering of the device and at the conclusion thereof the can is pressed firmly against the cover, the latter being forced against a plate, or chuck, 80, and accurately fitting over the same by virtue of the centering device previously mentioned. (Fig. 14)

While the cover is thus held firmly against the can (both parts being held against rotation), the roller 60 rolls the cover flange down over the body flange after which the roller 61 forces both flanges against the cylindrical body of the can. During this operation the chuck furnishes a solid backing to resist the inward thrust of the rollers and thereby insures a tight seam.

The seaming roller 60 is rotatably secured

to an arm 81 by means of a stud 82, said arm being rigidly secured to a stud 83. The stud 83 is free to turn in an opening in the gear 7 and at its upper end carries an arm 84 to the outer end of which is secured a cam 85. The roller 61 turns about a pivot 86 secured to the arm 87 which also pivots in the gear 7 by means of a stud 88, the upper end of said stud carrying a curved arm 89, the opposite end of which carries a cam 90. The cams 85 and 90 are operated by a cam member having two cam surfaces 91, 92 thereon, the first of which ensures a quick inward movement of the seaming rollers, and the second of which causes the seaming operation. When said cam member is moved upwardly, the cam 85 is first moved outwardly thereby moving the roller 60 inwardly, after which the cam 90 is moved outwardly thereby moving the roller 61 inwardly. The cam 90 has its beveled face in a higher plane than the cam 85. This mechanism insures the proper sequence of operation of the seaming rollers. The arm 89 is made sufficiently long to give a certain amount of spring to the roller 61, enabling it to run over the side seam of the can. The cam member is in the form of a sleeve (see Fig. 14), and is moved up and down by a ring 93, the latter being carried by a yoke 94, said yoke being pivoted at 95 and moved up and down by having its outer end engaged by the cam 96 which turns with the shaft 15.

35 In order to accommodate cams of different diameter without changing the entire seaming head, the cams 85, 90, may be adjusted by rotating them to permit the tapering pin in each case to be inserted into any one of a plurality of holes therein. The cam 85 is locked by the pin 97 and the cam 90 is locked by a pin 98, shown also in Fig. 13.

45 Just prior to the seaming operation when the can is being pressed up against the cover, the plate 80, which is mounted on the hollow shaft 101, is pressed upwardly against the action of the spring 102, providing a yielding pressure against the cover. 50 An ejector pin 103 passes through said hollow shaft and is moved downwardly by the lever 56 at the conclusion of the seaming operation, thereby insuring the removal of the covered can from the chuck and preventing sticking.

55 At the conclusion of the seaming operation the star wheel is given another 60° rotation, the can being guided along a support 104 with side rails 105, 106, which guide the can out of contact with the star wheel after which the operator lifts the can from the machine. The entire seaming mechanism is adjustable vertically to provide for cans of different heights; said seaming 60 mechanism is carried in a vertically adjust-

able head 107 which slides in vertical ways 108 (see Figs. 3 and 4), a gib 108^a being inserted between one of the ways and the head. The vertical adjustment of said head is determined by the pivoted lever 109, the lower end of which is eccentric, having a plurality of openings 110 therein through which a locking pin 111 may be passed. The head is then raised by rocking said lever to move said eccentric; said lever is pivoted to the head 107 by a pin 112, said eccentric resting on a stationary portion of the frame. The head is locked in place by a set screw 113.

70 The cover magazine is also vertically adjustable, being supported by a casting 114 which slides vertically on ways 115 and is adjusted and locked in place by means identical with that just described. The device for dropping the can covers one at a time 85 onto the cans is supported by the lever 54 on the head which supports the seaming mechanism and is adjustable therewith.

75 While I have described my invention with more or less minuteness, and as being embodied in certain precise forms; yet it will be understood that I do not desire to limit myself thereto unduly, and that it may be constructed in various other forms without departing from the scope of the appended 90 claims.

95 I claim:—

1. A can-closing machine comprising in combination a support, a rotatable seaming head, means for advancing said can to said seaming head, and means completely surrounding said can for holding said can during the seaming operation, said holding means being adjustable to accommodate cans of different diameter.

100 105 2. In a device of the class described, means external to the can for pressing it to circular outline, and means for adjusting said first means to accommodate it to the curvature of cans of different diameter.

110 115 3. A can-closing machine comprising a support, a seaming head, a pair of seaming rollers, an arm for each roller, an adjustable cam member on each of said arms, and a pair of cam surfaces which may be engaged directly by different parts of the cam surface of said adjustable cam members for moving said rollers to operating position.

120 125 4. In a device of the class described, a seaming head comprising a gear, a pair of integral arms pivotally mounted thereon, each arm carrying a roller and an adjustable member, and a pair of cam surfaces for operating the said adjustable members to move said rollers inward in a predetermined sequence, one of said arms being yielding to permit the roller to ride over the side seam of the can.

5. In a machine of the class described, an adjustable cover magazine comprising a 130

supporting plate, a plurality of vertical rods, pivotal supports for each rod whereby they may be swung to vary the distance between them, and means for adjusting said rods to any one of a series of definite positions.

6. In a machine of the class described, an adjustable cover magazine comprising a supporting plate, a plurality of vertical rods, pivotal supports for each rod whereby they may be swung to vary the distance between them, and a single means for simultaneously locking all of said rods in different positions of adjustment.

15. 7. A can-closing machine comprising a supporting frame, a seaming head vertically slidably thereon, a magazine also vertically slidably thereon, an eccentric member associated with each of said heads and movable to determine the position thereof, and means for locking said eccentric member in position.

25. 8. In a device of the class described, a supporting frame, a seaming head slidably mounted thereon, a pivoted cam for adjusting said seaming head, said cam having a plurality of openings therein at predetermined distances corresponding to definite adjustments of said head, and a locking pin 30 for locking said head in any position of adjustment.

9. In a device of the class described, a

seaming head, a rotatable conveyor, a cover magazine associated therewith, and a plurality of radially arranged arms pivoted to 35 said conveyor for removing the lowest cover from said magazine and transferring the same to said seaming head.

10. A can-closing machine comprising, in combination, a seaming head, a rotatable 40 conveyor for advancing the cans to said seaming head, a magazine for supplying covers to said cans, said seaming head, conveyor and magazine being adjustable to any one of a series of fixed positions to accommodate cans of different diameters.

11. A can-closing machine comprising, in combination, a seaming head, a rotatable conveyor for advancing the cans to said seaming head, a magazine for supplying 50 covers to said cans, said seaming head, conveyor and magazine being adjustable to any one of a series of fixed positions to accommodate cans of different diameters.

12. In a device of the class described, a 55 rotatable conveyor, a cover magazine adjacent thereto, a member pivotally mounted on said conveyor, and an inclined support engaged by said pivoted member to raise the same as it passes said magazine to thereby engage the lowermost cover and remove it from said magazine.

LAWRENCE DENNISON.
